UNITED STATES PATENT OFFICE.

MARSHALL F. CLAY, OF CANTON, OHIO.

WINDOW VENTILATOR.

Application filed May 12, 1924. Serial No. 712,653.

This invention relates to ventilator screens for windows and other structures, where it is desirable to provide ventilation, and the object of the improvement is to provide a 5 ventilator arranged to permit free passage of air but excluding rain, snow, dust and dirt as well as preventing a strong draught of air into the room.

Further objects of the invention are to 10 provide a ventilator including a metal frame provided with louvers and having a removable screen provided with a detachable screen fabric covering, whereby the screen fabric may be easily and readily removed 15 for the purpose of washing or renewing the same.

The above and other objects may be attained by constructing the ventilator in the manner illustrated in the accompanying 20 drawing, in which—

Figure 1 is an inside elevation of a ventilator embodying the invention;

Fig. 2, a section on the line 2—2, Fig. 1;

Fig. 3, an enlarged fragmentary section 25 of the screen frame, showing the manner in which the screen fabric is detachably secured to the frame;

Fig. 4, a detail plan elevation of the screen frame; and

Fig. 5, an edge elevation of the same.

Similar numerals indicate corresponding parts throughout the drawing.

The ventilator comprises a metal plate 1, having the louvers 2 stamped and bent outward therefrom at an angle to prevent rain or snow from passing through the same, while at the same time permitting the passage of sufficient air for ventilating purposes.

For the purpose of preventing rain or snow from being blown into the ends of the louvers, an angle strip 3 is spot welded or otherwise fastened to the plate at each end of the louvers. It will also be seen that the 40 construction of the louvers prevents even a strong wind from causing any considerable draught through the same.

The upper and lower edge portions of the plate are provided with the channel portions 4 which receive the end slides 5, each of which is preferably provided with the bent over upper and lower edges 6, slidably mounted in the channels 4 of the plate.

The inner end portion of each of the end 50 slides is cut away in any suitable form, such as indicated at 7, exposing the greater por-

tion of the louvers 2 in order to permit ventilating air to pass freely through the same.

For the purpose of preventing dirt and dust from passing through the ventilator into the room, a filter is provided which comprises a rectangular metal frame 8 mounted within the channels 4 and arranged to be slidably removed therefrom 60 and covered with a filter cloth 9 which may be cheesecloth or similar material.

This frame is provided upon its inner side with the angular flange 10 over which the fabric 9 is stretched, the edge portions of the fabric being folded back over the outer edges of the frame and detachably secured thereto by means of the channel clamping strips 11, the wider edge 12 thereof engaging the fabric between the flange 10 and the edge of the frame, tilting the clamping strip in the manner best shown in Fig. 3, causing the edge of the narrow side 13 of the strip to bind the fabric tightly against the adjacent side of the frame.

By tapering the ends of the flanges 10 downward from the intersection of the flanges to the edge of the frame, as shown at 14, the fabric will be further stretched at the corners, causing the clamping strips 11 to more tightly bind the fabric around the edges of the frame.

From the above, it will be obvious that a window ventilator is provided which is quickly adjustable to fit windows of various widths and which, while permitting sufficient ventilating air to pass therethrough, will prevent the passage of rain, snow, dust and dirt and strong gusts of wind from passing through the ventilator into the room.

It will also be obvious that the ventilator is provided with a removable screen provided with a detachable fabric screening material which may be easily and readily removed when it is necessary to wash or renew the same.

I claim:

1. A ventilator comprising a metal plate having louvers formed therein and provided with channel guides at its upper and lower edges, angle strips at each end of the louvers, a fabric filter mounted in the channel guides, and comprising a removable frame provided with a detachable covering of filtering material.

2. A ventilator comprising a metal plate and having channel guides at its upper and

lower edges and a detachable screen located in the guides and comprising a metal frame having an angle flange around its inner edge, a fabric filter covering the frame and channel attaching strips for clamping the filter to the edge portions of the frame.

3. A ventilator comprising a metal plate and having channel guides at its upper and lower edges and a detachable screen located in the guides and comprising a metal frame

having an angle flange around its inner edge, a fabric filter covering the frame and channel attaching strips for clamping the filter to the edge portions of the frame, the end portions of the angle flange being tapered toward the edge of the frame. 15

In testimony that I claim the above, I have hereunto subscribed my name.

MARSHALL F. CLAY.
